UNITED STATES PATENT OFFICE

156,829

PIPE LINE FITTING

Leland S. Hamer, Long Beach, Calif., assignor of
one-fourth to Paul A. Dewhirst, Los Angeles,
Calif.

Application October 18, 1948, Serial No. 149,154

Term of patent 14 years

(Cl. D91—1)

To all whom it may concern:

Be it known that I, Leland S. Hamer, a citizen of the United States, residing in the city of Long Beach, county of Los Angeles, and State of California, have invented a new, original, and ornamental Design for a Pipe Line Fitting, of which the following is a specification, reference being had to the accompanying drawings, forming a part thereof.

Fig. 1 is a perspective view of a pipe line fitting, showing my new design, showing two sides and one end thereof, and Fig. 2 is a perspective view of the pipe line fitting, showing two other sides and the other end thereof.

I claim:

The ornamental design for a pipe line fitting, as shown.

LELAND S. HAMER.
